METHOD OF TREATING HYDROCARBON OIL

Harold V. Atwell, White Plains, N. Y., assignor to
Gasoline Products Company, Inc., Newark,
N. J., a corporation of Delaware

Application June 10, 1933, Serial No. 675,213

2 Claims. (Cl. 196—48)

This invention relates to processes for the production of relatively light hydrocarbon oil, such as gasoline, from relatively heavy hydrocarbon oil, and pertains more particularly to processes 5 of this character wherein part of the once cracked oil is recycled in order to bring it to the desired specifications.

Prior practice has clearly indicated that, while certain types of hydrocarbon oils may be efficiently converted by cracking, into lighter products, e. g. those in the gasoline boiling range, under relatively high pressure, other oils should be cracked under lower pressures, in order to avoid the formation of excessive amounts of coke and 10 undesirably heavy products of polymerization. It has been found that relatively high pressures tend to cause more undesirable polymerization of recycle stock, for example, than of virgin stock, and accordingly various proposals have been made 15 for the cracking of the recycle stock in a separate zone wherein different conditions are imposed, than on the virgin stock. This would necessitate increased investments for the additional equipment necessary, with the result that in some 20 cases the separate treatment of recycle stock could hardly be justified from a financial viewpoint.

With these points in mind it is an object of my invention to provide a process for the treatment, 25 in a single cracking zone, of a plurality of oil stocks of the different types mentioned hereinbefore.

The above mentioned and other objects and advantages of my invention, and the manner of 30 attaining them, will be fully explained in the following description, taken in conjunction with the accompanying drawing.

The single figure of the drawing represents diagrammatically, an oil cracking system embodying my invention:

Referring more particularly to the drawing, reference numerals 3, 5, 8, and 10 indicate respectively a furnace or heater, reaction chamber or digester, separator, and fractionator, through 45 which the oil to be treated is passed in the usual cycle. Fresh charge, from a source not shown, is forced through line 1, by pump 2, into heater or furnace 3, which is preferably of the tubular type. The heated oil emerges from the furnace 3 through 50 pipe 4, at a temperature which may vary considerably, for example from 800° to 1200° F., but most suitably lies in the range of 850° to 975° F., preferably about 950° F., and is introduced into reaction chamber or digester 5, of the conventional 55 type, wherein cracking thereof takes place, with

resulting formation of lighter and heavier products. The temperature and time of passage of the oil through heater 3 may be sufficient to produce a considerable amount of cracking therein, or the major percentage of conversion may 5 take place in chamber 5. Alternatively, the cracking conditions may be so selected as to cause all of the cracking to take place in the coil, the reaction chamber being eliminated. These operations of heating and digesting are suitably carried out 10 at a fairly high pressure, e. g. from 500 to 3000 pounds per square inch, preferably about 1200 pounds per square inch, but higher or lower pressures may be provided. After undergoing cracking in the digester 5 the hot products of conversion 15 are passed through line 6, having reducing valve 7, into separator 8, in the usual manner. In the separator vapors separate from liquid residue, this residue being drawn off through line 16 for storage, or for any further conventional treatment, while the vapors are passed 20 through pipe 9 into fractionator 10, wherein the vapors are caused to flow through bubble trays, or other fractionating devices, with resulting partial condensation thereof. Vapors of the desired 25 end point pass off through vapor line 11 and condenser 12, the condensate being collected in receiver 13. A cooling coil 14 is provided for regulating the character of the vapors passing off from fractionator 10, and a similar cooling coil, 15, is 30 furnished for separator 8. Fresh charge or any other cooling medium may be forced through these coils.

Liquid reflux condensate formed in fractionator 10 is withdrawn therefrom through valved line 35 17 and is forced by pump 18 into line 1, for mixture with the fresh charge, and recycling through the system. A portion of this condensate may be diverted from the process through valved line 19 and cooler 20, into receiving drum 21, for 40 any desired further treatment, or use. And if desired additional charging stock of a different type may be introduced through auxiliary charging line 22 having pump 23. Valves 24, 25, 26, 27, and 28 provide the necessary control where- 45 by the relative volumes of the different stocks undergoing cracking may be regulated.

The ratio of recycle stock to fresh charge is so selected that cracking of both stocks is accomplished without the formation of such large 50 quantities of coke and heavy polymers, as would take place without the selection of the proper ratio. The ratio used, in accordance with my invention is such that the partial pressures on the two stocks undergoing treatment, are those 55

which correspond to the pressures found most suitable for the individual treatment of these stocks in separate cracking zones. Thus, if it has been found that a certain fresh charging stock is most successfully cracked under a pressure of, for example, 800 pounds per square inch, and that most efficient cracking of the recycle stock derived from that operation may be carried out at a lower pressure, of, for example, about 400 pounds per square inch, then where both stocks are being cracked in the same heating coil or furnace, by the recycling process, the amount of recycle stock should be about one-half of that of the fresh charge, the recycle ratio then being one to two. By so selecting the ratio it is determined that the partial pressures on these separate stocks while undergoing conversion at high temperature, i. e. upon approaching the end of the heating coil or during passage through the reaction chamber, will be approximately the same as the pressures found most suitable in separate operations. While it is true that the molecular weight of the recycle stock will be somewhat heavier than that of the fresh charge, this factor may be disregarded, substantial equality being assumed. On the basis of this assumption the ratio of recycle stock to fresh charge would be substantially the same as that desired for the corresponding cracking pressures. In the case assumed above, if 800 and 400 pounds pressure are found most suitable, respectively, for the cracking of fresh charge and recycle stock, then according to my invention the oil mixture in the ratio of one part recycle stock to two parts fresh charge would be cracked under a total pressure of 1200 pounds per square inch. The same principle applies where two different fresh charges are subjected to cracking in a single coil, recycling being used or not, as desired. If any stock is recycled then the total pressure would have to be apportioned among the three different stocks undergoing cracking, in the proper ratio to give the desired partial pressures.

Operation

In operation, fresh charge, for example A. P. I. Mid-Continent gas oil, is introduced through line 1, into heating furnace 3, wherein the oil is raised to an elevated temperature, which may vary considerably, but which is most suitably from 800 to 1200° F., and in any event high enough to vaporize most of the charging stock, preferably about 875 to 975° F., the outlet pressure on the heater being, for example, about 1200 pounds per square inch. During its passage through the heater the oil may be cracked to a greater or lesser degree, or in certain instances it may be desirable to heat the oil so quickly that very little cracking takes place in the heater. The outlet pressure on the heater may vary over a relatively wide range, e. g. from 500 to 3000 pounds per square inch, depending upon the type of stock being cracked, the time of passage, and the character of final product desired, but for the production of gasoline from a charging stock of the character mentioned, a pressure of about 1200 pounds per square inch is preferable. The highly heated stock is passed from the heater through the digestion chamber 5, within which the soaking or additional cracking takes place without the addition of heat, under substantially the same pressure as that of the heater, and the resulting products of conversion are passed through reducing valve 7 into the separator 8, which is maintained under a considerably lower

pressure than that of the heating and digesting zones. The pressure in the separator 8 may be, for example, about 200 pounds per square inch, although, as in the case of the cracking zone, this pressure may vary over a fairly broad range, for example, from 50 to 400 pounds per square inch, depending upon the character of the final product being produced. Most suitably, however, the pressure will be about 200 pounds per square inch in the case of the specific charging stock mentioned. In the chamber 8 vapors separate from liquid residue, the former being cooled by coil 15 to condense heavier undesired portions thereof, while the remaining uncondensed vapors pass over into the fractionator 10 and are there divided into a light vaporous portion, representing the final desired product, which passes off through vapor line 11 and condenser 12, the distillate being collected in receiver 13, and a reflux condensate. The character of this distillate is controlled in the well known manner by the cooling action of coil 14. The heavier portions of the vapors entering the fractionator are condensed, the reflux condensate being removed through line 17 and a proper amount thereof being recycled to the heater 3, wherein it is treated in mixture with the fresh charge. Where too much reflux condensate is produced to be used entirely as recycle stock, a portion of it may be diverted through line 19 to receiver 21, while in those cases where the reflux condensate is deficient in quantity, additional charge may be introduced through line 22, this charge being either of the same type as the recycle stock or of a different type. The amount of recycle stock may be one-half that of the fresh charge in this specific instance, whereby the partial pressures exerted on the two stocks will be approximately 400 pounds and 800 pounds per square inch respectively. In accordance with my invention when operating under ordinary cracking conditions of temperature and pressure on gas oil or similar charging stock the recycled stock should preferably not exceed one-half the fresh charge, in quantity. When extremely high rates of cracking are secured, e. g. in excess of 50% per pass, all of the recycle stock may be returned to the cracking operation. When the recycle ratio is selected in accordance with my invention as described hereinbefore the cracking rate may be increased since then the tendency toward the formation of coke is decreased, thereby permitting the higher temperatures and/or longer times of contact necessary for higher cracking rates. However, in the case of conventional moderate temperature and pressure cracking wherein a conversion to products in the gasoline boiling range, of about 15 to 25% per pass is obtained, a portion of the reflux condensate which is ordinarily recycled will have to be diverted from the process in order to establish balanced conditions. Preferably not over one-half of this stock is recycled under these cracking conditions.

If it is desired to crack three stocks in a single coil, the optimum cracking pressures thereof being found by experiment, 800, 400, and 200 pounds per square inch, for example, these stocks should be charged to the cracking zone in quantities bearing the ratios of four to two to one in the order given, under a total pressure of about 1400 pounds per square inch. While I have mentioned hereinbefore that the recycle stock will ordinarily not have changed in molecular weight sufficiently to require consideration of that point in selecting the ratios, in certain instances and

with particular charging stocks the molecular weight of the recycle stock may be changed sufficiently to justify a correction of the particular ratio thereof, and in the case where two different types of charging stocks are subjected to conversion in a single coil, these stocks being either virgin or cracked, or both, corrections for the difference in molecular weight may be necessary, the higher the molecular weight the greater the quantity of that stock needed to produce the desired partial pressure.

While I have particularly described the invention in connection with one conventional form of cracking system wherein a high pressure digestion chamber is used, the invention is applicable as well to other types of cracking processes, wherein no enlarged reaction chamber is used or wherein heating of the charge oil is brought about by admixture therewith, of highly heated fluids. The specific example given is intended merely for illustration, and it should be understood that various modifications and adaptations thereof may be made within the spirit of the invention as set forth in the appended claims.

25 I claim:

1. The process of treating hydrocarbon oil which comprises passing a clean gas oil charging stock through a heating zone wherein the temperature is raised to a value in excess of 900° F. 30 in the absence of added hydrogen, while maintaining a pressure in excess of about 1000 pounds per square inch on the oil leaving the heating zone, whereby conversion of the oil into lighter products takes place, separating the resulting 35 cracked products into vapors and a liquid residue, separating said vapors, by partial condensation, into a desired light vapor and a conden-

sate, and recycling condensate so separated for cracking with the fresh charge, and preventing the quantity of recycled condensate from exceeding one-half that of the fresh charge, said pressure first-mentioned being the sum of the pressure desired on the fresh oil and the pressure desired on the recycled condensate and said pressure desired on the fresh oil being at least double that desired on said condensate.

2. The process of treating hydrocarbon oil 10 which comprises passing a mixture of fresh charging oil and recycle stock through a heating zone wherein the oil is raised to a vapor phase cracking temperature and subjected to conversion, separating the resulting cracked products into vapors 15 and a liquid residue, subjecting said vapors to partial condensation to condense undesirable heavy fractions therefrom and leave vaporized the desired fractions, maintaining on the oil undergoing cracking a pressure equal to the sum 20 of the pressure desired on the fresh oil and the pressure desired on the recycle stock, said pressure desired on the fresh oil being at least double said pressure desired on the recycle stock, returning to said heating zone as said recycle stock 25 condensed undesirably heavy fractions of said vapors, in the same proportion with respect to the quantity of fresh charge as said pressure desired on said recycle stock bears to said pressure desired on the fresh oil, and preventing the quantity 30 of recycle stock returned to said heating zone in mixture with said fresh charging oil from exceeding one-half that of said fresh charging oil, by diverting any excess recycle stock from the process.

35 HAROLD V. ATWELL.
